UNITED STATES PATENT OFFICE

JOSEPH EUGÈNE BAPTISTE MAILLARD, OF NOGENT-LE-ROY, FRANCE

COMPACT AND VANITY SET

Application filed August 26, 1930, Serial No. 479,060, and in France September 2, 1929.

This invention relates to compacts and vanity sets.

The invention and its aims and objects will be readily understood from the following de-

scription taken in connection with the accompanying drawings, of an illustrative embodiment of the invention, the true scope of the invention being more particularly set forth in the appended claims.

10 In the drawings:

Fig. 1 is a vertical section of an illustrative form of pad with its case, embodying features of the invention;

Fig. 2 is a vertical section of the pad in 15 Fig. 1, in its case;

Fig. 3 is a top plan view of the case with the pad partially removed therefrom

Fig. 4 is a vertical section of a pad in its cuplike case;

20 Fig. 5 is a vertical section of the pad with a cake of rouge or other cosmetic in the center;

Figs. 6 and 7 are vertical sections of container pads, the under surface of which is of velvet having a central opening covered with 25 silk jersey;

Fig. 8 is a vertical section of a case containing a pad filled with cosmetic;

Fig. 9 is a top plan view of the case of Fig. 8 having one side of the handle raised;

30 Fig. 10 is a vertical section of a container pad with a velvet bottom having a central opening covered by silk jersey stitched to the velvet;

Fig. 11 is a bottom plan view of the pad 35 illustrated in Fig. 10;

Figs. 12 and 13 show complete compacts or vanity cases, the former being a top plan view and the latter a vertical section of an open vanity case or compact and enclosing 40 two cosmetic pads, one for face powder, the other for rouge or other cosmetic, a flexible eye-pencil and a lip-stick, the latter secured to the case fastening;

Fig. 14 is a vertical section of an illustrative embodiment of means for releasing or withdrawing the flexible eye-pencil;

Fig. 15 is a plan view of the snap fastening 50 for the case, having secured thereto the lip-stick which may thus serve as a handle for the case;

Figs. 16 and 17 are sectional details of the container and its interchangeable cup for the black or other coloring matter for the flexible eye-pencil.

It will be apparent that the combination 55 and cooperation of several means or instrumentalities are necessary to the securing of a satisfactory makeup and one of the objects of the present invention is to provide these several things, namely case, mirror, powder, 60 pad, cosmetic-pad, lip-stick and eye-pencil, or the more essential ones, of a construction and in a form and combination that shall be efficient and convenient for securing the result desired.

In accordance with my invention dispensing means for the cosmetics (face powder, rouge or other product, pasty or otherwise) is provided, said means insuring the automatic escape of the cosmetic therefrom and 70 constituting at the same time a puff (powder-puff) for applying the cosmetic. To this end said dispensing means is provided with permeable means upon one side. In the case 75 of face powder or other relatively finely divided cosmetics, said permeable means may conveniently consist of a fabric sufficiently loosely woven to provide the permeability desired, such as silk jersey for example. In the case of cosmetics that are not sufficiently 80 finely divided or of a pasty nature, the desired permeability may be secured by using a more closely woven fabric or other material, provided with a plurality of suitable perforations for the passage of the product. In the 85 case of pasty products, I obtain good results by using a sheet of rubber provided with perforations. The other side of said dispensing means will preferably be of material impermeable to the substance it is to contain.

In the case of face powder or rouge in cake or powdered form, or any other cosmetic for that matter, the permeable portion of silk jersey, for example, may be surrounded by means to facilitate the even distribution and application of the cosmetic, silk velvet, cotton, or wool fabric for example, the powder, rouge or other cosmetic that escapes through the permeable portion being evenly distributable by the velvet or wool or cotton 100.

fabric. To this end the velvet or cotton or wool fabric may be provided with a central opening covered by silk jersey that may be stitched to the velvet at its marginal portion.

3 Referring to Figs. 1, 2, 3 and 4, an illustrative form of dispensing means provided herein may consist of a container pad having an impermeable back 1 secured circumferentially to an annular cushion 2 of light rubber, celluloid or other flexible material. The powder 6 is confined in the space between the back 1 and the dispensing surface of silk jersey 7. A thin disk 3 rests upon a packing 5 against which it is pressed by a spring 4 between said disk and the back 1, the powder being thus prevented from escaping around the circumference of said disk. The circumferential edges of the parts 5, 7 and 8 are turned up over the edge of the back 1 and secured thereto by an adhesive or in any other suitable manner. A large meshed fabric is preferably inserted between the powder and the dispensing surface 7 to afford the necessary resistance to the spring 4.

25 The device is closed at the rear by the top or cover 9 which is secured to the back 1 and may be provided with a handle 10 secured at 12 to the handle 11 of the case. The case comprises a bottom 15 of velvet having its circumferential edge turned upwardly about an annular cushion 16 to which it is secured by an adhesive or in any other suitable manner, said cushion being preferably of flexible rubber or any other suitable flexible material.

30 By projecting the finger inwardly through an opening 13 provided in the handle 11 carried by the top 14 of the case, the container pad can be pushed out of its casing. The handle 11 and top 14 are preferably of leather, cloth or textile fabric, but any suitable material may be used. The top 14 is secured at its circumferential edge portion to the annular cushion 16 with the exception of a sufficiently large portion for the passage of the container pad into and out of the case.

35 In Fig. 4 the case comprises a ring 19 of metal, cardboard, celluloid or other suitable material, provided with an annular cushion 20, velvet 18 being stretched over the ring to form a cup, the upturned circumferential portion of the velvet being secured in any suitable manner to the annular cushion 20.

40 In Fig. 5 the pad has a circular bottom 22 of velvet, the circumferential edge of which is turned inwardly as shown at 23, and over this edge is secured in any suitable manner the circular top 9 provided with a handle 10. The container 25 of jersey silk 27 for the powder, rouge or other cosmetic is secured by an adhesive or in any other suitable manner within the depressed portion 24 of the bottom 22. A thread 28 may be provided connecting the outer face of the silk jersey 27 to the center of the bottom 22, to prevent

the silk jersey from becoming overslack as the cosmetic is dispensed.

45 In Figs. 6, 7, 10 and 11, the powder or other cosmetic 31 extends throughout the entire surface of the container pad and escapes therefrom through the permeable central portion of silk jersey 27.

50 In Fig. 6 the circumferential edge of the jersey silk 27 is turned in over a ring 32 and is secured to the marginal portion 24 of the part 22 by stitching, adhesive or in any other suitable manner. In Fig. 7 the circumferential edge of the silk jersey is turned back over the marginal edge of the part 22, as shown at 33, and is secured thereto by stitching, adhesive, or in any other suitable manner.

55 In Figs. 8 and 9, the case comprises a bottom 34, preferably of silk velvet or wool or cotton fabric, to serve to distribute the powder over the part to which it is to be applied. The top comprises two parts 35 and 38 stitched to the bottom 34 by overcasting at 37. The part 35 has a handle portion 36 and the part 38 a handle portion 39. The part 43 constitutes a hinge, permitting the cover part 38 to be raised to place a container pad 40 in the case or withdraw it therefrom.

60 The bottom 34 of the case thus constitutes a powder puff when placed in a powder box and contains the pad 40 which may contain rouge or other cosmetic, the whole thus furnishing a compact comprising a powder puff and a rouge container within the latter.

65 The pad 40 may have a handle 42 and may be of any construction herein described or of any other suitable construction.

70 In Figs. 10 and 11, the silk jersey 27 is placed within the pad, a thin washer of paper 44 being inserted between the jersey and the velvet, the edges of the jersey and the velvet being stitched together at 45.

75 Within the scope of the invention, these container pads or puffs and their cases may be of any suitable material. Preferably, however, they will be made of pliable or flexible material such as textile fabrics or other cloths, the pads in certain cases being of rubber and the cases in some instances of soft leather, as already mentioned. Made of such materials these container pads and cases are of pleasing appearance, take up less space, are very light and, in spite of their relatively small dimensions, their capacity is materially greater than that of more voluminous and heavier metal containers.

80 Referring to Figs. 12 to 17, the compact or vanity case comprises the outer cups 46, 48 and an inner cup 47, preferably of metal. The cup 48 contains a mirror 74 and the cups 46 and 47 are provided with pockets 49 and 50 for a powder pad 57 and other cosmetic pads 58, respectively.

85 A flexible eye-pencil 61 is received in an angular compartment 59 formed by plate 60

of the cup 47. A projection 73 retains said pencil in place and a bell crank lever 71, see Fig. 14, serves to dislodge said pencil for use. The tampon-like end 62 of said pencil 5 receives the eye black from a removable receptacle 67 provided with a small lever 70 and plate 68 which has a sliding engagement with the opening 66 of the frame 65, which latter is closed by a cover 63 hinged at 64.

10 The mirror 74 being separated from the powder pad by the cup 47 will not be tarnished by the powder. The three cups 46, 47 and 48 are hinged together at 51 and are held closed by a snap fastener 52, 53. A lip-15 stick 56 may be secured to the fastener member 53, as shown in Fig. 15 and may serve as a handle for the vanity case.

I am aware that my invention may be embodied in other specific forms without departing from the spirit or essential attributes thereof, and I therefore desire the present embodiment to be considered in all respects as illustrative and not restrictive, reference being had to the appended claims rather than 25 to the foregoing description to indicate the scope of the invention.

I claim:

1. A compact or vanity case comprising two circular members hinged together at their 30 edges, said members being formed to provide a container, one of said members having retaining means for a pad, said retaining means formed adjacent the edge of the last mentioned member with an arcuate recess for receiving a flexible pencil.

2. A compact or vanity case comprising two circular members, means forming a hinge for connecting said members at one portion of their edges, said members being formed to 40 provide a container, one of said members being cup-shaped and having across the portion of its top at the side thereof opposite said hinge a plate-like member for retaining a pad, said plate-like member being formed 45 with an arcuate recess paralleling the edge of said cup-shaped member in closely adjacent relation to said edge for receiving a flexible pencil.

3. A compact or vanity case having, in 50 combination, three cup-shaped members hinged together adjacent portions of their edges, said members so arranged that when in closed position the intermediate member 55 will be received within one of the outer members and the bottom wall of said intermediate member will be spaced from the bottom wall of the other outer member, the last mentioned outer member formed with a compartment 60 for removably receiving a pad, a mirror carried interiorly of the other outer member at the bottom wall thereof, said intermediate member being formed interiorly thereof with an arcuate groove for receiving a flexible pencil and also formed with a compart-

ment adjacent an end of said groove for receiving a container for cosmetic substance.

4. A compact or vanity case having, in combination, three circular cup-shaped members, means forming a hinge for connecting 70 said members at portions of their edges, said members so arranged that when in closed position the intermediate member will be received within one of the outer members and the bottom wall of said intermediate member will be spaced from the bottom wall of the other outer member, the last mentioned outer member formed with a compartment for removably receiving a pad, a mirror carried interiorly of the other outer member at the 75 bottom wall thereof, said intermediate member having means for retaining a pad therein, said means being formed with an arcuate recess paralleling the edge of said intermediate member in closely adjacent relation thereto for receiving a flexible pencil.

5. A compact or vanity case having, in combination, three cup-shaped members hinged together adjacent portions of their edges, said members so arranged that when in closed position the intermediate member will be received within one of the outer members and the bottom wall of said intermediate member will be spaced from the bottom wall of the other outer member; said last mentioned outer member and said intermediate member formed with means for removably retaining pads, and one of them being formed with an arcuate groove for receiving a flexible pencil.

6. A flat compact pad comprising a container for cosmetic material having at one flat side thereof a rigid backing, the opposite flat side wall thereof being formed of flexible impervious material and having an opening closed by a sheet of pervious material, and means connecting said last mentioned flat side wall to said rigid backing providing for movement of said flat side in the plane thereof relative to said backing, said means including flexible peripheral walls for said container.

7. A flat compact pad comprising a container for cosmetic material having at one flat side thereof a rigid backing, the opposite flat side wall thereof being formed of flexible impervious napped textile material and having a centrally positioned opening closed by a sheet of pervious material, and means connecting said last mentioned flat side wall to said rigid backing providing for movement of said flat side in the plane thereof relative to said backing, said means including flexible peripheral walls for said container.

8. A flat compact pad comprising a container for cosmetic material having at one flat side thereof a rigid backing, the opposite flat side wall thereof being formed of flexible impervious material and having an opening closed by a sheet of pervious flexible textile

material, and means connecting said last mentioned flat side wall to said rigid backing providing for movement of said flat side in the plane thereof relative to said backing, said means including flexible peripheral walls for said container.

9. A flat circular compact pad comprising a container for cosmetic material having at the flat upper side thereof a rigid backing of 10 slightly less diameter than said pad, the opposite flat side of said container comprising a lower wall formed of flexible impervious napped textile material having a centrally positioned opening closed by a sheet of pervious textile material, means connecting said 15 lower flat wall to said rigid backing providing for movement of said wall in the plane thereof relative to said backing, said means including flexible peripheral walls for said 20 container and flexible upper flat wall portions surrounding said backing formed integrally with said lower flat wall.

In testimony whereof, I have signed my name to this specification.

25 JOSEPH EUGÈNE BAPTISTE MAILLARD.
